FRAME FOR A ROTATABLE CONDIMENT RACK

William B. Sewell, Los Angeles, Calif., assignor to
Sewell Products Inc., Los Angeles, Calif., a corporation of California

Application February 26, 1951, Serial No. 14,319

Term of patent 3½ years

(Cl. D44—29)

To all whom it may concern:

Be it known that I, William B. Sewell, a citizen of the United States, residing in the city of Los Angeles, county of Los Angeles, and State of California, have invented a new, original, and ornamental Design for a Frame for a Rotatable Condiment Rack, of which the following is a specification, reference being had to the accompanying drawings, forming a part thereof.

Fig. 1 is a top perspective view of a frame for a rotatable condiment rack, showing my new design;

Fig. 2 is a top plan view;

Fig. 3 is a bottom plan view; and

Fig. 4 is a side elevational view thereof.

I claim:

The ornamental design for a frame for a rotatable condiment rack, as shown.

WILLIAM B. SEWELL.
